DESIGN FOR A BOTTLE CAP REMOVER

Elsie M. Wilkins, Rome, N. Y.

Application July 8, 1933, Serial No. 48,667

Term of patent 14 years

To all whom it may concern:

Be it known that I, ELSIE M. WILKINS, a citizen of the United States, residing at Rome, county of Oneida, and State of New York, have invented a new, original, and ornamental Design for Bottle Cap Removers, of which the following is a specification, reference being had to the accompanying drawing, forming part thereof.

The figure is a plan view of a bottle cap remover showing my new design.

I claim:—

The ornamental design for a bottle cap remover, substantially as shown.

ELsie M. Wilkins.
